183,733

POWER MOWER ENGINE SHROUD

John Gale, Carver, Minn., assignor to Toro Manufacturing Corporation, Minneapolis, Minn., a corporation of Minnesota

Application February 26, 1958, Serial No. 49,801

Term of patent 14 years

(Cl. D40—1)

Fig. 1 is a front perspective view of a power mower engine shroud embodying my new design, viewed from the right;

Fig. 2 is a front perspective view of the same, viewed from the left;

Fig. 3 is a top plan view of the same;

Fig. 4 is a side elevational view of the same, viewed from the left;

Fig. 5 is a front elevational view of the same;

Fig. 6 is a side elevational view, viewed from the right; and

Fig. 7 is a rear elevational view of the same.

I claim:

The ornamental design for a power mower engine shroud, as shown.
